UNITED STATES PATENT OFFICE.

WALTER F. STIMPSON, OF MILAN, MICHIGAN.

DESIGN FOR A FACE-PLATE FOR COMPUTING-SCALES.

SPECIFICATION forming part of Design No. 29,065, dated July 19, 1898.

Application filed November 5, 1897. Serial No. 657,572. Term of patent 14 years.

To all whom it may concern:

Be it known that I, WALTER F. STIMPSON, a citizen of the United States, residing at Milan, in the county of Washtenaw and State 5 of Michigan, have invented and produced a new and original Design for Face-Plates for Computing-Scales, of which the following is a specification, reference being had therein to the accompanying drawings.

10 The invention relates to an original and new design for face-plates for computing scales; and it consists in the configuration shown and hereinafter described.

In the drawings, Figure 1 is an elevation 15 of the plate embodying the design, and Fig. 2 is an edge view.

A designates a circular plate having a segmental opening B formed at one side leading

in from the edge. The opposite edge walls of this opening are substantially uniform or 20 alike throughout, as shown.

The leading feature of the design is the circular plate having the segmental opening therein with substantially like edge walls, as 25 shown.

Having thus described the invention, what is claimed as new and original, and desired to be secured by Letters Patent, is—

The design for a face-plate for computing scales, substantially as shown and described. 30

In testimony whereof I affix my signature in presence of two witnesses.

WALTER F. STIMPSON.
